(57) **CLAIM**

The ornamental design for a light therapy device, as shown and described.

DESCRIPTION

FIG. 1 is a front elevation view of a light therapy device showing the new design;

FIG. 2 is a rear elevation view thereof;

FIG. 3 is a left side view thereof;

FIG. 4 is a right side view thereof;

FIG. 5 is a top plan view thereof; and,

FIG. 6 is a bottom plan view thereof.

The even-length broken lines shown in the drawings illustrate portions of the light therapy device that form no part of the claimed design.

1 Claim, 6 Drawing Sheets
